UNITED STATES PATENT OFFICE.

GEORGE ALBERT MOUNTCASTLE, OF ARRINGDALE, VIRGINIA.

LOGGING-CAR.

SPECIFICATION forming part of Letters Patent No. 645,510, dated March 13, 1900.

Application filed July 8, 1899. Serial No. 723,196. (No model.)

To all whom it may concern:

Be it known that I, GEORGE ALBERT MOUNTCASTLE, a citizen of the United States, residing at Arringdale, in the county of Southampton 5 and State of Virginia, have invented certain new and useful Improvements in Logging-Cars; and I do hereby declare the following to be a full, clear, and exact description of the invention, such as will enable others 10 skilled in the art to which it appertains to make and use the same.

This invention relates to logging-cars. As generally constructed the standards are fitted at their lower ends into sockets provided 15 at the ends of the bolsters. The logs by reason of their peculiar formation, being round in cross-section, exert a material outward pressure against the inner edges or sides of the standards, thereby rendering it exceedingly 20 difficult to remove them from their sockets when it is required to dump the load.

The object of this invention is to facilitate the detachment of the standards from the bolster and to enable the operation to be quickly 25 and safely performed without requiring the intervention of tools, levers, or other implements to effect the desired result.

For a full description of the invention and the merits thereof and also to acquire a 30 knowledge of the details of construction of the means for effecting the result reference is to be had to the following description and the drawings hereto attached.

While the essential and characteristic features of the invention are necessarily susceptible of modification, still the preferred embodiment of the invention is illustrated in the accompanying drawings, in which—

Figure 1 is a rear view of an end portion 35 of a bolster, showing the application of the invention. Fig. 2 is a perspective view thereof. Fig. 3 is a top plan view, the dotted lines showing the operation of the device.

Corresponding and like parts are referred 40 to in the following description and indicated in all the views of the drawings by the same reference characters.

The bolster 1 has its end portion cut away 45 from one side to within a short distance of 50 the opposite side, forming a seat 2, into which the lower end of the standard 3 is fitted.

This seat is bounded on two of its sides by walls 4 and 5, formed by cutting away the end portion of the bolster, and on the other two sides by a yoke 6 and the projecting end 55 portion of an iron 7, secured to the bolster. The transverse wall 5 slants, being inclined outwardly and downwardly at its lower end, so as to prevent downward slipping of the standard when in position, the lower end of 60 said standard being inclined on the side adjacent to the wall 5, so as to effect the desired result.

The yoke 6 is a flat bar or plate of metal having its ends reduced and formed into eyes 65 which are looped into the iron 7 and a locking-slide 8. The yoke extends across the outer side of the standard and confines the latter between it and the wall 5 and is adapted to swing outward at the end attached to the 70 slide 8, so as to release the standard.

The locking-slide 8 may be of any form and as shown is an oblong link, its free end portion being engaged by a keeper 9, applied to the side of the bolster. A projection 10 extends laterally from the bolster and engages with the locking-slide at a point intermediate of its ends. This projection forms a support 75 for the slide and limits it in its sliding movements.

A catch is provided to engage with the locking-slide 8 and hold it in an operative position. This catch consists of a pivoted member 11, having a recurved or reversely-bent hooked end 12, adapted to engage with the end 80 of the slide 8 and enter an opening in the side of the bolster, so as to secure the part 8. The journal 13 of the catch has an arm, handle, or lever 14 extending therefrom in the same direction as the member 11, the outer end portion of the arm being deflected or curved, as shown at 15, to provide a convenient grip for the hand when it is required to operate the catch to release the locking-slide of the yoke.

The parts 11, 12, 13, and 14 are integral, being formed from a single rod or bar of metal by bending the same into the shape substantially as shown. The outer end portion of the arm 14 is flattened and slotted to receive a staple 16, a hook, pin, or analogous device 17 90 being passed through the staple to prevent outward displacement of the arm 14 when en-

gaged therewith. A chain or like connection 18 fastens the part 17 to the bolster, thereby preventing loss or displacement thereof.

A bearing is applied to the bolster to receive the journal 13 and consists of a plate 19, having one end bent about at a right angle, as shown at 20, and let into the bolster and having its opposite end portion folded, as shown at 21, and receiving the journal 13 in the fold, the folded end portion being secured to the plate and the latter to the bolster by the same bolt or fastening 22.

When the standard is in position, the yoke closes the open side of the seat 2 and retains the standard in place, the locking-slide 8 is engaged with the keeper 9 by being passed therethrough, the catch is applied to the slide 8, and the arm of the catch is fastened by the staple 16 and the part 17 in the manner set forth. When it is required to release the standard, the arm 14 is liberated by withdrawing the hook or pin 17 from the staple and is moved outward at its free end away from the bolster. This operation withdraws the catch from the locking-slide 8, which moves forward under the strain of the standard due to the load pressing outward thereon.

Having thus described the invention, what is claimed as new is—

- o 1. The combination with a bolster provided with a seat for the standard, of a yoke for confining the standard in said seat and pivoted at one end, a locking-slide loosely connected with the free end of the yoke, a keeper for engagement with the slide, and a catch independent of said keeper for locking the slide.
- o 5. The combination with a bolster provided with a seat for the standard, of a yoke for con-

fining the standard in said seat, a locking-slide in engagement with the free end of the yoke, a catch pivoted upon the side of the bolster for engagement with the locking-slide, and an arm for moving the catch toward and from said slide.

3. The combination with a bolster provided with a seat for the standard, of a yoke for confining the standard in said seat, a locking-slide in engagement with the free end of the yoke, a catch pivoted upon the side of the bolster for engagement with the locking-slide, an arm for moving the catch toward and from said slide, and means for securing the arm against displacement.

4. The combination with a bolster having a seat, and a yoke for closing the open side of the seat, of a locking-slide having loose connection with the yoke, a projection for directing the slide in its sliding movements, and means for securing the slide, substantially as specified.

5. The combination with a bolster having a seat, and a yoke for closing the open side of the seat, of a locking-slide having loose connection with the yoke, a projection for directing the slide in its sliding movements, a keeper, a pivoted catch, an arm, a staple for passing through a slot of the arm, and a locking device coöoperating with the staple to hold the arm in place, substantially as described.

In testimony whereof I affix my signature in presence of two witnesses.

GEORGE ALBERT MOUNTCASTLE. [L.S.]
